UNITED STATES PATENT OFFICE.

JOSEPH VICTOR HIGGINS, OF BAYOU CHENE, LOUISIANA.

DEVICE FOR CONTROLLING HORSES.

SPECIFICATION forming part of Letters Patent No. 746,080, dated December 8, 1903.

Application filed July 26, 1903. Serial No. 167,024. (No model.)

To all whom it may concern:

Be it known that I, JOSEPH VICTOR HIGGINS, a citizen of the United States, residing at Bayou Chene, in the parish of St. Martin and State of Louisiana, have invented a new and useful Device for Controlling Fractious Horses, of which the following is a specification.

This invention relates to devices for controlling fractious and fretful horses while driving the same; and it has for its object to provide a device of this class which shall be capable of adjustment, whereby the horses may be normally held in to any desired extent, so that there shall be no danger of their getting the advantage of the driver, and which shall, furthermore, be so constructed that in the event of impending danger or a runaway the horses may be instantly and powerfully checked and controlled, or even thrown, if it shall be found necessary to do so.

A further object of the invention is to provide a device of this class with means whereby the powerful restraint which it may occasionally be found necessary to bring to bear upon the animals may be instantaneously released at any moment, so as to avoid danger of injury to the animals.

With these and other objects in view, as will appear as the nature of the invention is better understood, the invention consists in the improved construction, arrangement, and combination of parts, which will be herein-after fully described, and particularly pointed out in the claims.

In the accompanying drawings, Figure 1 is a perspective view of a device constructed in accordance with the principles of my invention. Fig. 2 is a transverse sectional view taken longitudinally through the winch or roller. Fig. 3 is a detail view showing the releasing-lever thrown for the purpose of releasing the clutch-controlling winch.

Corresponding parts in the several figures are indicated by similar numerals of reference.

The frame of my improved device is composed of side pieces 11, which are in the form of brackets having foot pieces or lugs 2, provided with perforations 3 for the passage of screws or bolts, whereby the device may be secured in position for operation. Each of

said side pieces is also provided with a laterally-extending flange-piece 4, cast or formed integrally therewith for the purpose of sustaining the frame rigidly in position for operation. The two side pieces of the frame are connected mainly by means of a transverse brace 5, provided near its ends with shoulders 6, abutting upon the inner sides of the side frame-pieces 1, and having screw-threaded ends upon which washers 7 and nuts 8 are mounted, thus securing the side pieces together. Said side pieces are also connected and spaced by means of an apron 9, suitably secured to their upper or front sides.

The upper front ends of the brackets 11 are provided with bearings for the ends of a roller or winch 10, having a transverse opening 11, and provided with set-screws 12, the inner ends of which extend into the said transverse opening or slot. The shaft or axis of said roller projects at one end of the frame and carries a clutch element 13, which may be secured in position thereon in any suitable manner—such as, for instance, by means of set-screws 14. The shaft at this point is also preferably squared to prevent the clutch element from rotating thereon. A coacting clutch element 15 is mounted loosely upon the shaft and is provided with an annular recess or groove 16, engaged by the bifurcated end of a flat spring 17, which is securely mounted upon one of the projecting ends of the cross-brace 5. This spring, which is of considerable strength, serves to hold the clutch elements 13 and 15 normally in engagement with each other.

The clutch member 15 is provided with a crank or handle 16^a, which is preferably formed integrally therewith and which partakes of the movement of said clutch member on the shaft, which latter when the clutch members 15 and 13 are in engagement may be rotated by means of said crank. Adjacent to the crank is placed a slidably cup-shaped collar 19, and a spring 20, socketed in said collar, is interposed between the latter and the knob or head 21, permanently mounted upon the outer end of the shaft, thereby serving to force the crank and the clutch member 15 into engagement with the clutch member 13, with which it is normally in contact.

The clutch member 13 is provided at its periphery with teeth or ratchets 22, normally engaged by a pawl 23, which is fulerumed upon the side of the frame and which is normally held in engagement with said ratchets by means of a suitably-disposed flat spring 24, which may be pivotally connected with the side of the frame by means of a pin or bolt 25 and which is extended under and permanently disposed upon the lug 26 in such a manner as to bear downward upon the engaging end of the pawl 23, which is thereby normally held in engagement with the ratchet portion of the clutch member 13. The opposite end of the pawl 23 is connected by means of a link 27 with an operating-lever 28, one end of which is provided with a handle 29. The inner or active end of said lever is adapted to engage between the side of the frame 20 and a cam-shaped lug 30, formed upon the inner side of the flat spring 17. It will be understood from the foregoing description that the clutch members 13 and 15 are normally in engagement with each other, being thus held by means of the flat spring 17, assisted by the coiled spring 20. The crank 16^a is likewise held in operative position, being an integral part of the clutch member 15. In operation the device is mounted upon the dashboard or in any other suitable position of the vehicle to which it is to be attached. An auxiliary line 32 is led from the bit of the horse or from the bit of each horse, as the case may be, to the winch or roller 10, in the slot of which said line or lines are firmly secured by means of the set-screws 12. By rotating the winch by means of the crank these lines may be tightened to any extent that may be deemed necessary or desirable in order to make it impossible for the horse or horses to seize the bits by the teeth, and thereby get beyond the control of the driver. Of course if only one horse of the team is fractious one of the lead-lines may be connected with the roller so loosely that it will not be tightened up to any desirable extent by the rotation of the winch. The latter will be held in the position to which it is adjusted by means of the pawl 23, engaging the ratchets upon the periphery of the clutch member 13. If the horses while driving should show a disposition to run away or to get beyond control, the winch may be operated by means of the crank to still further tighten the lead-lines, which may be quickly accomplished to such an extent that the heads of the horses will be forced in a rearward direction until they look back at the carriage. This operation may even be continued until the horses are thrown, the animals being choked by thus straining their heads backward. At the same time the strain may be instantaneously released by manipulating the lever 28, the end of which will engage between the side of the frame and the cam-shaped projection upon the flat spring 17, thus forcing the free end of the latter in

an outward direction and causing the clutch members to be temporarily disengaged from each other. At the same time the link 27, which connects the lever 28 with the pawl 23, will disengage the latter from the toothed circumference of the clutch member 13, thereby permitting the winch to revolve freely in a reverse direction while the lead-lines are being unwound therefrom, this being obviously accomplished without the crank rotating with the shaft, which might be more or less dangerous to the occupants of the vehicle. By simply disengaging the lever 28 from engagement with the cam upon the spring 17 the device will be restored to operative position.

This device is to be constructed throughout of such material as, without being excessively heavy, will be fully able to resist any strain to which it may be subjected. It may also be made of various sizes, and I desire it to be understood that while the device has been herein described as being for the purpose of controlling fractious horses it may within the scope of the invention be utilized as a hoisting-machine or for other purposes for which it may be deemed available.

Having thus described my invention, I claim—

1. In a device of the class described, a frame, a winch journaled in said frame and having a longitudinal slot and set-screws engaging the body of the winch and extending into the slot thereof.

2. In a device of the class described, a frame, a winch journaled in said frame, a clutch member secured upon the shaft of said winch, a coöperating clutch member mounted movably upon said shaft and having an operating-crank and an annular groove, and a flat spring secured to the side of the frame and having a bifurcated end engaging the annular groove of the movable clutch member.

3. In a device of the class described, a frame comprising sides connected by a cross-brace having projecting ends and nuts upon said ends, a winch journaled in said frame, a stationary clutch member upon the shaft of said winch, a clutch member mounted movably upon said shaft and having an operating-crank and an annular groove, and a flat spring upon one of the projecting ends of the connecting-brace and having a bifurcated end engaging the annular groove of the movable clutch member.

4. In a device of the class described, a frame, a winch journaled in said frame, a clutch member fixedly connected with said winch, a movable clutch member having an annular groove, a flat spring connected with the frame and having a bifurcated end engaging the annular groove of the movable clutch member and provided on its inner side with a cam-shaped projection, and a lever pivotally connected with the frame and engaging said cam-shaped projection.

5. In a device of the class described, a frame, a winch journaled therein, a clutch

member connected fixedly with the winch and having a ratchet-toothed edge, a movable clutch member, means for holding the latter normally in contact with the fixed clutch member, a spring-actuated pawl normally engaging the ratchet-tooth edge of the stationary clutch member, and means for simultaneously throwing said pawl and the movable clutch member out of engagement with the stationary clutch member.

6. In a device of the class described, a frame, a winch journaled therein, a stationary clutch member fixedly connected with said winch and having peripheral teeth or ratchets, a movable clutch member having an annular groove, a flat spring engaging said annular groove and holding the movable clutch member normally in engagement with the fixed clutch member, a spring-actuated pawl normally engaging the ratchet-teeth of

the fixed clutch member, a cam-shaped projection upon the inner side of the flat spring and a lever adapted to engage said cam-shaped projection, and a link connecting said lever with the pawl engaging the toothed edge 25 of the fixed clutch member.

7. In a device of the class described, a winch, means for rotating said winch, means for restraining said winch against reverse movement, and means for simultaneously disengaging the rotating means and the restraining means, thereby permitting the winch to rotate reversely.

In testimony that I claim the foregoing as my own I have hereto affixed my signature in 35 the presence of two witnesses.

JOSEPH VICTOR HIGGINS.
